UNITED STATES PATENT OFFICE

144,608

DESIGN FOR AN ELECTRIC TOOL UNIT

Francesco Collura, New York, N. Y., assignor to
Millers Falls Company, Greenfield, Mass., a cor-
poration of Massachusetts

Application June 1, 1945, Serial No. 119,837

Term of patent 14 years

(Cl. D54—14)

To all whom it may concern:

Be it known that I, Francesco Collura, a citizen of the United States, residing at New York, in the county and State of New York, have invented a new, original, and ornamental Design for an Electric Tool Unit, of which the following is a specification, reference being had to the accompanying drawing, forming a part thereof.

Fig. 1 is a side elevational view of an electric tool unit showing my design;

Fig. 2 is a top elevational view thereof; and

Fig. 3 is an end elevational view looking from the left end of the tool as shown in Figs. 1 and 2.

The side of this tool unit opposite to that shown in Fig. 1 is substantially like the side shown, with the exception of the bulging portion which appears only on one side.

I claim:

The ornamental design for an electric tool unit, as shown and described.

FRANCESCO COLLURA.
